United States Patent [19]

Henke et al.

[11] Patent Number: Des. 310,012

[45] Date of Patent: ** Aug. 21, 1990

[54] **HAND-HELD SANDER**

[75] Inventors: **David R. Henke**, Maple Grove;
David J. Ruha, Hopkins, both of
Minn.

[73] Assignee: **Warner Manufacturing Company**,
Minneapolis, Minn.

[**] Term: 14 Years

[21] Appl. No.: 905,163

[22] Filed: Sep. 11, 1986

[52] U.S. Cl. D8/90; D8/45

[58] Field of Search D8/14, 90-93;
D32/51; D28/59; 51/370, 371, 372, 384, 390,
391, 392, 393, 211 R, 212; 15/144 A, 245; 29/81
H, 81 J, 81 L, 80
